DESIGN FOR A PIANO CASE

Samuel E. Zack, Chicago, Ill., assignor to Gulbransen Company, Chicago, Ill., a corporation of Illinois

Application August 22, 1936, Serial No. 64,519

Term of patent 3½ years

To all whom it may concern:

Be it known that I, Samuel E. Zack, a citizen of the United States, residing at Chicago, in the county of Cook and State of Illinois, have invented a new, original, and ornamental Design for a Piano Case, of which the following is a specification, reference being had to the accompanying drawing, forming a part thereof.

The single figure is a perspective view of a piano case showing my new design.

I claim:

The ornamental design for a piano case, as shown.

SAMUEL E. ZACK.
